UNITED STATES PATENT OFFICE.

GEORGE M. WILLIAMS, OF ELIZABETH, NEW JERSEY, ASSIGNOR TO P. LORILLARD COMPANY, OF NEW YORK, N. Y., A CORPORATION OF NEW JERSEY.

BALE-BAND TIGHTENER.

1,324,090.

Specification of Letters Patent.

Patented Dec. 9, 1919.

Application filed October 19, 1915. Serial No. 56,733.

To all whom it may concern:

Be it known that I, GEORGE M. WILLIAMS, a citizen of the United States, residing at Elizabeth, in the county of Union and State 5 of New Jersey, have invented new and useful Improvements in Bale-Band Tighteners, of which the following is a specification.

This invention relates to certain novel and useful improvements in a tool for stretching and tightening metallic straps or bands about bales, boxes and other forms of packages.

To effectively and securely apply a metallic band or strap to a package, especially 15 when the latter possesses any degree of flexibility, resiliency or compressibility, the ends of the strap or band should be pulled or drawn toward each other by the exercise of considerable tension on such ends, and this 20 tension should be maintained while the ends are being joined by a suitable fastening device.

In the present instance it is my purpose to provide a tool or implement through the 25 agency of which the strap or band may be drawn taut about the package and the ends brought into overlapping relation and held in such position while the fastening device for securing the ends together is being applied.

The tool or implement constituting this invention is particularly adapted for tensioning and holding the strap or band on the package with the ends of the strap or band 35 in overlapping relation, and when these ends are so correlated they may be securely and conveniently joined by means of an eyelet such as forms the subject matter of my Design Patent, #46,487, dated September 29, 40 1914, and which eyelet may be applied by means of the upsetting tool set forth in Letters Patent, #1,123,153, granted to me December 29, 1914. However, I wish it to be understood that this tool may be used under 45 conditions where it is desired to tension the strap or band and bring the ends of the latter in juxtaposition, but not into overlapping relation, the ends, under such circumstances, being coupled by any well known 50 form of bale-buckle suitable for the purpose.

I also propose to provide a tool of this character which will embody the desired features of simplicity, durability and efficiency, and through the medium of which the strap

or band may be rapidly, safely and neatly secured about the package and under the proper tension. 55

With the above recited objects and others of a similar nature in view, my invention consists in the construction, combination and 60 arrangement of parts set forth in and falling within the scope of the appended claims.

In the accompanying drawings—

Figure 1 is a view showing the tool in use on a box or bale to which a strap or band is 65 being applied, the ends of the latter being brought into overlapping relation.

Fig. 2 is a view of the opposite side of the tool from that shown in Fig. 1.

Fig. 3 is a top plan view. 70

Fig. 4 is a view in side elevation with one of the side plates of the body or frame removed and showing the interior rack and pinion construction.

Fig. 5 is a cross sectional view taken on 75 the line 5—5 of Fig. 3.

Figs. 6 and 7 are detail perspective views of the parts of one of the clamps.

Fig. 8 is a perspective view of the overlapping connected ends of a strap or band 80 which have been fastened by an eyelet after the strap or band has been tensioned by means of my device.

Referring now to the accompanying drawings in detail the letter A indicates the body 85 portion or frame of the tool as an entirety, this frame, as well as other parts of the tool, being preferably constructed of suitable metal, such as tool steel and constituting a support. This frame includes the base plate 90

1, the under face of which is adapted to rest or seat on the package being strapped, and the rack and pinion housing 2. This housing embodies a wall 3 preferably formed rigid with the base plate and having an enlarged central section 4 provided with an approximately circular recess 5 adapted to accommodate the toothed pinion 6 which is mounted upon the inner end of the shaft 7.

This shaft 7 extends transversely through 95 and is supported by the enlarged section 4 of the wall, as is clearly shown in Fig. 5 of the drawings. At its lower portion the recess 5 opens into the longitudinal slot or

groove 8, the latter forming a guideway for 100 the sliding rack bar 9, the teeth of which mesh with the teeth of the pinion 6 as will be readily understood. The side plate 11

completes the housing and may be removably attached to the wall 3 by suitable screws or bolts as shown at 12. The wall 3 between the enlarged central section and one end of 5 such wall is cut away as at 14 so that when the side plate 11 is in position a space or way 15 results in which may travel the block 16 integral with one end of the rack bar. The plate 11 opposite the cutaway portion 10 of the wall 3 is provided with a pair of longitudinally extending parallel slots shown at 17 and 18.

In the construction of my improved tool, I employ a pair of clamping devices indicated at B and C respectively. The clamping device B is stationarily or rigidly secured to the body or frame A adjacent one end portion of the latter, and this clamping device is adapted in use to hold one end 20 of the strap or band, while the clamping device C is movably connected with the opposite end portion of the frame or body A, and is adapted to grip or clamp the opposite end of the strap or band. It will 25 be understood that the clamping device C is adapted to be shifted or moved relative to the clamping device B so that the two ends of the band or strap may be drawn into overlapping relation. As hereinafter 30 described the clamping device C is connected to and movable with the rack bar, and in addition has a limited amount of play or movement relative to the rack bar.

These clamping devices B and C have 35 certain structural features in common. For instance, each embodies an angular member 19 and a swinging or pivoted cam member 20. Each angular member includes a vertical plate 21 adapted to lie against the side 40 plate 11 and a horizontally and outwardly extending foot plate 22 adapted to coöperate with the toe section 23 of the cam member of the clamp for the purpose of gripping and holding the end of the strap or band.

45 Each cam member is pivoted adjacent its toe to the vertical plate of the angular member of the cam by means of a suitable pin 24, and the bearing surface of the toe member, as well as the top face of the foot plate 50 of each clamping device, is preferably roughened or corrugated to obtain a better gripping action.

The stationary clamping device may be rigidly fastened to the side plate 11 adjacent one end of the latter by suitable means such as the screws or bolts 25.

The movable clamping member C is preferably connected in operative position as follows:

55 The vertical plate 21 of the angular member of the clamping device C is provided with a pair of alining elongated slots 26 through which pass the screws 27, these screws also passing through the lower elongated slot 18 in the side plate 11 of the

housing, the shanks of the screws being socketed in the block 16 of the rack bar. Above the slots 26, the vertical plate is formed with a relative long elongated slot 28 through which passes the relatively long 70 pin 29, the shank of this pin also passing through the upper elongated slot 17 in the side plate 11 and is connected with the block 16 of the rack bar. The outer end portion of this long pin 29 extends above the foot 75 plate of the angular member of the clamp, and also extends through the elongated slot 30 formed in the cam member of this clamp C.

By this manner of connecting the clamp 80 member C with the rack bar, it will be seen that not only will such clamping device C move with the rack bar when the latter is operated, but may also have a limited amount of movement relative to such rack 85 bar, thereby enabling the gripping action of the clamping device to be increased. For instance, by this arrangement it will be understood that when the clamping member C is moved toward the stationary clamping member B, the greater the tension exerted on the band being tightened, the greater will be the gripping action of this clamping device upon the end of the band, thereby obviating the liability of such band end 90 slipping or pulling through the clamping device.

In order to actuate the pinion and thus shift the rack bar I provide a hand lever 31, the lower end of which is bored as at 32 100 for the passage of the interiorly threaded sleeve 33 and through this sleeve is adapted to pass the reduced threaded end 34 of the shaft 7. The outer end of the sleeve 33 has fast therewith a small ratchet gear 105 35 which is adapted to be engaged by the pawl 36 pivoted as at 37 to the lever 31. The opposite or inner end of the sleeve 33 has fast therewith a small collar 38 which is recessed to receive the enlarged or shouldered section 40 of the shaft 7, a pin 41 fastening the collar to the shaft 7. This shaft 7 has also mounted thereon the gear wheel 42 fast with such shaft, while 43 indicates a bearing collar interposed between this gear 42 and the adjacent face of the wall 3 of the frame. A dog 44 is pivoted as at 45 to the wall 3, the tooth of this dog being adapted to engage with the teeth of the gear 42 so as to hold the latter against 115 back lash or backward rotation as will be readily understood, a small hand grip 46 being employed for moving the dog out of engagement with the gear when desired.

From the above description taken in connection with the accompanying drawings the construction and manner of employing my improved band tightener will be readily apparent.

When it is desired to use the tool in 120 125

stretching and tightening a strap or band about a bale or other package, such tool is positioned as shown in Fig. 1 so that the base plate and the foot plates of the tool 5 will rest on the top of the package. The ends of the band are then inserted between the cam members and the foot plates of the clamping devices, and such cam members swung or moved to locking position so that 10 the toes of these cam members will grip and bind the ends of the bands against the foot plates of the clamps. The ends of the bands thus being secured the hand lever is operated so that the pivoted pawl will engage 15 the ratchet wheel and turn the latter. As this ratchet wheel is fast with the sleeve, and as the sleeve in turn is connected through the collar at its end with the shaft 7, such shaft will be turned and a rotary motion im- 20 parted to the pinion, this movement of the pinion in turn being transmitted to the rack bar so that the latter will move or slide in the housing. As the end of the rack bar carrying the block 16 is drawn inward, the 25 clamping device C will be drawn toward the clamping device B, thus pulling on the band or strap and bringing the two ends of the strap into overlapping relation. When this has been accomplished, and the gear wheel 30 42 and consequently the shaft 7 is locked against backward rotation by means of the dog 44, the band will be held securely in position although under tension. An eye- 35 let E may then be employed to connect the ends of the band by a suitable upsetting tool, as illustrated in my prior Patent #1,123,153 above mentioned.

It will be seen that owing to the fact that the overlapping ends are held above or 40 clear of the surface of the bale or package by means of the foot plates, sufficient room exists to enable the upsetting tool to be employed to apply the rivets for connecting the ends of the straps, without interference with 45 the operation of such tool by the body of the bale and therefore the band or strap may be drawn taut and fastened securely, quickly and conveniently.

After the overlapping ends of the band 50 have been riveted together the device may be removed by simply releasing the pivoted cam members which grip the ends of the band.

While I have herein shown and described one particular embodiment of my invention 55 I wish it to be understood that I do not confine myself to the precise details of construction herein set forth by way of illustration, as modification and variation may be made without departing from the spirit of the 60 invention or exceeding the scope of the appended claims.

What I claim is

1. In a tool of the class described, the combination with a frame having a face adapted to rest on the package, of a rack bar sliding

in the frame, a clamping device connected to and movable with the rack bar and adapted to grip one end of a band, a second clamping device connected with the frame and adapted to grip the opposite end of the band, 70 each clamping device including a relatively thin plate member carrying a gripping surface insertible between the band and the opposed package face, and means for actuating the rack bar to draw one end of the band toward the other end. 75

2. In a tool of the class described, the combination with a frame having a face adapted to rest on the package, of a slidable rack bar movable on the frame, a clamping device loosely connected with the frame and also connected to the rack bar and adapted to travel with said rack bar, a second clamping device stationarily mounted on the frame, each clamping device including a relatively thin plate member carrying a gripping surface insertible between the band and the opposed package face, and means for actuating the rack bar to move the clamping device carried thereby relative to 85 the stationary clamping device. 90

3. In a tool of the class described, the combination with a frame having a face adapted to rest on the package, of a pair of clamping devices connected therewith, said 95 devices being mounted in alinement and adapted to grip the opposite ends of a band, each device including a relatively thin plate member carrying a gripping surface insertible between the band and the opposed 100 package face, and means supported from the frame and connected with one of the clamping devices for moving the same relative to the other clamping device.

4. In a tool of the class described, the combination with a frame, of means carried by the frame for holding one end of a band, a clamping device mounted on the frame for clamping the opposite end of the band, each device including a relatively thin plate 105 member carrying a gripping surface insertible between the band and the opposed package face, a sliding member carried by the frame, said device including a pair of gripping elements one of which is pivoted 110 on the other, both of said elements being connected to said sliding member, and means for actuating the sliding member to cause the movement of the clamping device. 115

5. In a tool of the class described, the 120 combination with a supporting frame, of a pair of alining clamping devices carried thereby and adapted to grip the opposite ends of a band, each clamping device including an angular plate one of said plates 125 being slidably mounted on and guided by said frame, and a cam member pivoted to one portion of the angular plate, and co-operating with the other portion of the angular plate to grip the band, and means 130

4
operatively engaging both plate and member of one of said devices for moving it relative to the other clamping device.

6. In a tool of the class described, the combination with a frame, of a clamping device carried by the frame, and including an angular member slidably mounted on and guided by said frame and comprising a vertical plate, and a relatively thin horizontal 10 foot plate and a cam member pivoted to the vertical plate of the angular member.

7. In a tool of the class described, the combination of a frame including a base adapted to rest upon a package, a housing 15 mounted upon the base, a clamp rigidly connected with the housing and having an element adapted to support one end of a band above the adjacent face of the package, and a second clamping device loosely connected 20 with the housing and also having an element adapted to support the other end of the band above the adjacent face of the package, and means for actuating the last mentioned clamping device to draw one end of the band 25 toward the other end.

8. In a tool of the class described, the combination with a base having a seat face, a housing mounted thereon, a rack bar slid- 30 able in the housing, means including a pin-
ion for reciprocating the rack bar, a clamp-
ing device loosely mounted on the housing and also connected with the rack bar to move with said rack bar and a second clamping device connected with the housing and 35 spaced apart from but arranged in alinement with the first mentioned clamping device, each device including an element hav-
ing a face substantially flush with said seat face.

40 9. In a tool of the class described, the combination with a base plate, of a housing mounted upon said base plate, a slid-
able rack bar and a pinion located within the housing, a shaft for said pinion, means in-
cluding a lever and a pawl and ratchet 45 mechanism for rotating the shaft to actuate

the pinion, a clamping device rigidly fas-
tened at one outer wall of the housing, a
second clamping device arranged in aline-
ment with the first mentioned clamping de-
vice, and means extending through said 50 outer wall of the housing for connecting the
second clamping device with the rack bar
whereby upon the movement of the rack bar
said second clamping device may be moved 55 relative to the first mentioned clamping de-
vice.

10. In a tool of the class described and in combination, a support, a reciprocating member carried by the support, and a grip-
ping device slidably mounted on and guided 60 by the support and comprising a pair of
gripping elements pivotally connected to
provide gripping action, and means for con-
necting both elements to said member to 65 permit movement relative thereto.

11. In a tool of the class described and in combination, a support, a reciprocating member carried by the support, and a grip-
ping device comprising a pair of gripping 70 elements pivotally connected to provide
gripping action, and means for connecting
both elements to said member; said means
including complemental pin and slot con-
nections whereby one element may move 75 pivotally relative to the other element to
tighten the grip during the band-tightening
movements.

12. In a tool of the class described, the combination with a support, of a member 80 movable thereon and a gripping device oper-
atively connected to and bodily movable
with said member and also movable relative
to such member, said device being slidably
mounted on and guided by the support. 85

In testimony whereof I have hereunto set
my hand in presence of two subscribing wit-
nesses.

GEORGE M. WILLIAMS.
